ORE-FLOTATION APPARATUS AND METHOD

Application filed August 6, 1927. Serial No. 211,059.

This invention pertains to ore flotation apparatus and method in which pulp formed by mixing finely pulverized ore with water and necessary flotation reagents is treated by 5 the passage of air through it so as to cause a froth of air bubbles to be formed on the surface of the pulp. The bubbles carry in suspension a high percentage of the crushed mineral particles, which are carried off with the 10 froth and subsequently recovered therefrom by suitable processes.

In the present invention air under pressure is admitted to the bottom of the pulp and rises therethrough. This has been done by 15 previous inventors, and that part of the process is not claimed as new. My invention pertains particularly to the treatment of the pulp after the injected air has set the mass in circulation in the flotation cell.

20 In some previous designs of apparatus for the same purpose the operation is very inefficient because the air serves simply to agitate the pulp, thereby forming only a thin layer of dense, heavily laden froth which, because 25 of lack of supporting aeration, must be removed promptly from the cell. On account of the thinness of the froth layer in this type of cell the pulp level must be kept close to the overflow lip with resultant danger of pulp 30 slopping over into the concentrate launder.

Another type of cell has an air lift with an air pressure chamber above the deflecting cap of the air lift. The purpose of the pressure chamber is to build up sufficient pressure in 35 the air compartment to cause the pulp discharged from the air lift to pass beneath baffles into the froth compartments. As a result of this construction much of the air used in the air lift is carried beneath the baffles 40 into the spitzkasten without being finely disseminated or emulsified, thereby causing considerable agitation in the spitzkasten, thus not only preventing the formation of new froth but also tending to break down the fragile 45 bubble column already formed. In order to prevent such action it is necessary to provide a cascading discharge of the pulp from beneath the deflector cap and a free exit to the air for all large bubbles from the air lift and to permit 50 only fine froth-forming bubbles to pass

underneath the baffles into the froth compartments.

Another type of flotation cell uses an air lift only to circulate the pulp and discharge a comparatively small quantity of froth on the 55 top surface of the pulp in the cell. This does not produce a bubble column froth flotation result, but only a surface tension flotation effect which has been found inadequate for the intended purpose.

60 The present invention is designed to overcome the defects and shortcomings of the above and similar processes by providing a cell which operates with true bubble column action and produces a deep bubble column in 65 a wide flotation cell.

The principal object of the present invention is to bring about an extremely fine subdivision and dispersion of a large quantity 70 of air in the pulp without the use of any porous medium, and to produce a typical bubble column froth flotation process. To accomplish this result the invention provides for the rise of pulp and air at high velocity in the air lift compartment; for rapid circulation 75 of pulp between the air lift and froth compartment; for cascade action in discharging pulp from beneath the deflector through an air space; for means permitting adjustment of the size and velocity of the cascade; 80 for baffles adjustable to permit only air in extremely finely subdivided condition to pass into the froth compartment, thereby reducing agitation in the froth compartment to a minimum; for extremely fine division of the air 85 in the froth compartment whereby a sweeping bubble action is established which has a strong bubble column supporting action, thereby permitting operation of the cell with deep bubble column and wide froth compartment; and for 90 free and unrestricted exit to the atmosphere of air not finely dispersed in the pulp.

95 To these and other ends the invention comprises the novel features and combinations of elements hereinafter described and shown in the drawings, which by way of illustration show what I now consider to be the preferred form of the invention. In the drawings,

Fig. 1 is a cross-section of the cell in operation, on the line 1—1 of Fig. 3.

Fig. 2 is a plan view of the cell.

Fig. 3 is a side view of Fig. 2 partly broken away to show the interior construction.

Fig. 4 is an enlarged detail view on the line 4—4 of Fig. 3, showing the adjustable baffle supports.

In its essential features the cell comprises 10 a receptacle 10, into the lower portion of which air is introduced through a row of drop pipes 12 projecting downwardly from the header 14, to which air is supplied under pressure through pipe 16 provided with a regulating valve 18.

Extending lengthwise of the cell on both sides of the drop pipes are plates 20 forming an air lift compartment 22 through which rises the air discharged from the open lower 20 ends of the drop pipes.

The receptacle is normally filled with pulp to the level indicated by line 24 and the large bubbles of air which emerge from the drop pipes rise through the air lift compartment 25 and set up a rapid upward circulation of pulp through the air lift compartment, drawing pulp from the cell and discharging it against the under side of deflector cap 26 which is adjustably supported on pipes 12 by set screws 28. The purpose of this adjustment is to control the thickness, velocity and directional flow of the cascade. The ore pulp is directed by deflector 26 downwardly over the tops of plates 20 through the space between plates 20 and baffles 30 back into the cell. Baffle plates 30 extend the full length of the cell and are adjustably secured to the ends thereof by brackets 32 which are bolted to the vertically and horizontally slotted 35 brackets 34 substantially as shown in Fig. 4 so that baffles 30 may be adjusted vertically, horizontally, and angularly, relatively to the cell.

The space between plates 20 and 30 is occupied by air through which the returning pulp is forced in the form of a cascade, resulting in considerable entrainment of air by the cascade in addition to the air already contained in the falling pulp. The cascade 50 action also results in considerable agitation in the pulp into which the cascade falls at 36 between plates 20 and 30.

If all of this agitation were transmitted to bubble column 40, which is a mass of bubbles 55 somewhat similar to soap bubbles, the bubble column would be caused to collapse. The amount of agitation transmitted from 36 to 40 may be regulated by the position of the adjustable baffles 30, which may be set, as 60 already described, to give the most advantageous results.

Baffles 30 serve not only to form a compartment or air space through which the pulp passing over the tops of plates 20 may fall as 65 a cascade, but also to protect the bubble col-

umn 40 from direct action of the cascade. At the head of the cascade, all air not sufficiently broken up to be entrained in the pulp makes its escape to the air compartment and thence to the atmosphere as indicated by the arrows 70 in spaces 42 provided between the upper edge of the baffles 30 and the under side of lips 44 which form part of deflector 26.

The action of the cascade as it passes through the air space between plates 20 and 30 serves to entrain additional air in the falling pulp and to finely divide and emulsify that air. Any air not properly entrained and emulsified is liberated as the cascade falls into the pulp and is free to escape through outlet 42. As circulation continues, due to action of the air lift, the air emulsion formed by the above action passes underneath adjustable baffles 30 and adds to the volume of froth in the bubble column. The lower edge of this adjustable baffle should not be so deeply submerged as to interfere with the directional force of the cascade in causing the froth-forming bubbles to pass thereunder and to maintain the bubble column formed in the zone of quiescence. The thickness and velocity of the cascade is adjustable, depending upon the location of deflector plate 26.

When the height of the bubble column rises above the level of weirs 46 the froth overflows into launders 48 to pass therefrom to the concentrate discharge outlets 50.

Raw pulp is supplied to chamber 52 on the end of the cell and passes therefrom into the cell through opening 54 provided therefor in the end of the cell. The tailings discharge takes place from the other end of the cell through opening 56 and over adjustable weir 58 to the tailings discharge 60.

The above apparatus and method of operation insure rapid circulation of pulp due to the air lift, cascading of the pulp through an air space (freely open to the atmosphere) in the compartments formed by the adjustable baffles and the air lift compartment, violent impingement of the cascading stream of pulp directly on the pulp surface in this compartment and a zone of quiescence in the cell, with the result that a wide, deep column of froth is formed in the cell.

Study of the above flotation process in a full size glass apparatus indicates that the distance through which the cascading pulp falls from beneath the deflector cap to the pulp surface is of importance in producing effective aeration in the cell. A fall of 8 or 10 inches has been found effective. The amount of aeration decreases as this distance is decreased until with only 2 or 3 inches fall, aeration ceases entirely. The amount of aeration also depends on the volume and initial velocity of the cascading stream as it leaves the underside of the deflecting cap. The velocity of the stream of pulp at this point should be made as great as is consistent with the cir-

5 culation of a very considerable volume of pulp. It has been found in practice that the volume of pulp circulated should be several times that of the pulp being fed to the apparatus in order to get maximum aerating effect.

10 The position of the adjustable baffles is also of importance in securing the maximum aerating effect. They should be so adjusted that the outer surface of the cascading pulp comes in contact with the baffle on the line where the baffle enters the pulp. The position of the descending cascading pulp as shown in the drawing has been found to give the best results, that is, a distinct air space should re-

15 main between the outer surface of the descending stream and the adjustable baffle and between the inner surface of the descending stream and the wall of the air lift compartment. These air spaces should be freely open

20 to the atmosphere through passages sufficiently large to insure that the air in the air spaces is under atmospheric pressure only. It has been found that if the air in these air spaces is at a pressure in excess of atmospheric pressure

25 sure the fine dissemination of air in the ore pulp by the cascade action is hindered or even entirely prevented, dependent upon the amount of excess air pressure present, and there is a tendency for coarse undisseminated

30 air to escape from the air spaces beneath the adjustable baffles and into the outer part of the cell or zone of quiescence and thus seriously interfere with or entirely prevent formation of a deep column of froth in the outer

35 part of the cell.

It is to be understood that the invention is not limited to the specific apparatus and method herein illustrated and described but can be embodied in other forms without departure from its spirit as defined by the following claims.

I claim—

1. In an ore flotation apparatus, a receptacle adapted to contain ore pulp and to collect and separate froth, an uplift chamber within said receptacle, projecting a substantial distance above the normal pulp level, means for injecting air into the pulp therein to maintain a rapid upward movement of the pulp within said uplift chamber, means at the top of said uplift chamber for directing said circulating pulp substantially directly downwardly in an expanding cascade, through an air space freely open to the atmosphere, and for causing said cascade to impinge directly on the surface of the pulp, whereby the pulp is effectively aerated with froth-forming bubbles, and means for directing the aerated pulp under the pulp level of the froth chamber to exclude large bubbles.

2. In an ore flotation apparatus, a receptacle adapted to contain ore pulp, and to collect and separate froth, an uplift chamber within said receptacle, projecting a substantial distance above the normal pulp level,

means for injecting air into the pulp therein to maintain a rapid upward movement of the pulp therethrough to a height above the normal pulp level, means at the top of said uplift chamber for directing said circulating pulp substantially directly downwardly in an expanding cascade, through a compartment freely open to the atmosphere adjacent to said uplift chamber, and for causing said cascade to impinge directly on the surface of the pulp in said compartment, whereby the pulp is effectively aerated with froth-forming bubbles, and means for collecting and separating the froth.

3. In an ore flotation apparatus, a receptacle adapted to contain ore pulp and to collect and separate froth, an uplift chamber within said receptacle, projecting a substantial distance above the normal pulp level, a baffle spaced from said uplift chamber, adjustable toward and away therefrom and projecting into the pulp, and defining a compartment freely open to the atmosphere, means for injecting air into the pulp in said uplift chamber to maintain a rapid upward movement of the pulp therethrough to a substantial height above the normal pulp level and means at the top of said uplift chamber for directing said circulating pulp substantially directly downwardly through said compartment in expanding cascade formation on to the surface of the pulp in said compartment, whereby the pulp is effectively aerated with froth-forming bubbles, and means for collecting and separating the froth.

4. In an ore flotation apparatus, a receptacle adapted to contain ore pulp and to collect and separate froth, an uplift chamber within said receptacle, projecting a substantial distance above the normal pulp level, means for injecting air into the pulp therein to maintain a rapid upward movement of the pulp therethrough to a height above the normal pulp level, means forming a compartment outside the chamber and freely open to the air, means at the top of said uplift chamber for directing said circulating pulp directly and substantially downwardly through said compartment in cascade formation, said means being adjustable for varying the size and velocity of said cascade, and for causing said cascade to impinge directly on the surface of the pulp in said compartment, whereby the pulp is effectively aerated with froth-forming bubbles, and means for collecting and separating the froth.

5. A method of treating ore pulp by the flotation process comprising injecting air into a portion of ore pulp in an uplift chamber to cause a rapid upward movement of pulp therethrough to a substantial height above the normal pulp level in a receptacle adjacent to said uplift chamber, and then projecting the moving pulp in expanding cascade for-

- mation substantially directly downwardly upon the surface of a partially isolated portion of the pulp in said receptacle, and so regulating the rate of discharge of said moving pulp from the uplift chamber and the distance through which the pulp is permitted to fall in cascade as to insure that the moving pulp will attain a velocity at the point of its impingement upon the surface of said partially isolated portion of the pulp sufficient to promote effective aeration of the pulp with froth-forming bubbles, while confining any large non-froth-forming bubbles to said partially isolated portion of the pulp.
6. A method of treating ore pulp by the flotation process comprising injecting air into a portion of ore pulp in an uplift chamber to cause a rapid upward movement of pulp therethrough to a substantial height above the normal pulp level in a compartment adjacent to said uplift chamber, and then projecting the moving pulp in expanding cascade formation substantially directly downwardly upon the surface of the pulp that is in this adjacent compartment, and so regulating the rate of discharge of said moving pulp from the uplift chamber and the distance through which the pulp is permitted to fall in cascade as to insure that the moving pulp will attain a velocity at the point of its impingement upon the surface of a partially isolated portion of the pulp sufficient to promote effective aeration of the pulp with froth-forming bubbles and the transference of these froth-forming bubbles to the main body of the pulp in a zone of relative quiescence and exclude the large non-froth-forming bubbles, whereby a wide deep column of froth is formed.
7. A method of treating ore pulp by the flotation process comprising injecting air into a portion of ore pulp in an uplift chamber to cause a rapid upward movement of pulp therethrough to a substantial height above the normal pulp level in a compartment adjacent to said uplift chamber, and then projecting the moving pulp in expanding cascade formation directly upon the surface of that portion of the pulp in this adjacent compartment, and so regulating the rate of discharge of said moving pulp from the uplift chamber and the distance through which the pulp is permitted to fall in cascade as to insure that the moving pulp will attain a velocity at the point of its impingement upon the surface of a partially isolated portion of the pulp sufficient to promote effective aeration of the pulp with froth-forming bubbles and the transference of these froth-forming bubbles to the main body of the pulp in a zone of relative quiescence and excluding the large non-froth-forming bubbles, whereby a wide deep column of froth is formed, and permitting free ingress and egress of air from said adjacent compartment to the atmosphere.
8. In an ore flotation apparatus, a receptacle adapted to contain ore pulp, an uplift chamber within said receptacle, a baffle spaced from said uplift chamber and depending beneath the normal pulp level in said receptacle, means for injecting air into the pulp in said uplift chamber to maintain a rapid upward movement of pulp therethrough to a substantial height above the normal pulp level and means at the top of said uplift chamber for directing said circulating pulp downwardly through said compartment in cascade formation and in direct impingement upon the surface of the pulp in said compartment, the outlet from said uplift chamber being disposed at a sufficient elevation above the normal pulp level to insure that the descending cascade of pulp and air shall attain such a velocity at the point of impingement as to cause substantial entrainment of air therewith from the atmosphere through which it falls and to penetrate the body of pulp sufficiently to carry the froth-forming bubbles present in, and formed by such cascade to be carried beneath the baffle and to rise through the main body of pulp in that portion of the receptacle beyond said baffle while the large non-froth-forming bubbles escape to the atmosphere from the cascade compartment.
9. In an ore flotation apparatus, a receptacle adapted to contain ore pulp, an uplift chamber within said receptacle, a baffle spaced from said uplift chamber, and projecting into the pulp, and defining a compartment freely open to the atmosphere, means for injecting air into the uplift chamber to maintain a rapid upward movement of pulp therethrough to a substantial height above the normal pulp level, and means at the top of said uplift chamber for directing the pulp downwardly through said compartment, in expanding cascade formation onto the surfaces of the pulp in said compartment, the expanding cascade being slightly inclined toward the baffle, whereby the pulp is effectively aerated with froth-forming bubbles, and means for collecting and separating the froth.
10. A method of treating ore pulp by the flotation process comprising injecting air into a portion of ore pulp in an uplift chamber to cause a rapid upward movement of pulp therethrough to a substantial height above the normal pulp level in a compartment adjacent to said uplift chamber, and then projecting the moving pulp downwardly in an expanding cascade which has a slight outward inclination upon the surface of that portion of the pulp that is in this adjacent compartment and so regulating the discharge of said moving pulp from the uplift chamber and the distance through which the pulp is permitted to fall in cascade as to insure that the moving pulp will attain a velocity at the points of its impingement upon the surface of a partially isolated portion of the pulp sufficient to pro-

5
mote effective aeration of the pulp with froth-forming bubbles and the transference of these froth-forming bubbles to the main body of the pulp in a zone of relative quiescence and excluding the large non-froth-forming bubbles, whereby a wide deep column of froth is formed, and permitting free ingress and egress of air from said adjacent compartment to the atmosphere.
